(57) **CLAIM**

An ornamental design for a threaded nozzle insert, as shown and described.

DESCRIPTION

FIG. 1 depicts a perspective view of a threaded nozzle insert.

FIG. 2 depicts a front view thereof.

FIG. 3 depicts a rear view thereof.

FIG. 4 depicts a right side-view thereof.

FIG. 5 depicts a left side-view thereof.

FIG. 6 depicts a top view thereof.

FIG. 7 depicts a bottom view thereof.

FIG. 8 depicts a section view thereof along the section line shown in FIG. 6; and,

FIG. 9 depicts a detail view thereof for the region circled in FIG. 8.

A threaded nozzle insert is depicted in the accompanying Figures.

Broken, dashed black lines are used to represent features that do not form a part of the claimed design. Broken, dot-dash-dot lines depict boundary lines that indicate transitions between claimed and unclaimed regions of the depicted article and do not form part of the claimed design. Broken, dash-dot-dot-dash lines depict cross-section drawing section lines or detail view boundary lines.
